UNITED STATES PATENT OFFICE.

ALBERT D. GROVER, OF NEW YORK, N. Y.

TAILPIECE FOR BANJOS AND THE LIKE.

1,350,310.

Specification of Letters Patent. Patented Aug. 24, 1920.

Application filed January 7, 1918. Serial No. 210,756.

To all whom it may concern:

Be it known that I, ALBERT D. GROVER, a citizen of the United States, and resident of New York, county of New York, and State 5 of New York, have invented certain new and useful Improvements in Tailpieces for Banjos and the like, of which the following is a specification.

The object of my invention is to provide 10 a new and improved tailpiece for string instruments, such as the banjo and the like. As those skilled in the art know, there are several kinds or styles of banjos in use today. The most common of these instruments 15 are provided, respectively, with four, five, six and eight strings. Heretofore, a separate tailpiece was necessary with each kind of banjo. The tailpiece of my invention is readily adaptable for all of the different kinds of banjos or allied instruments, 20 being adapted to receive from four to eight strings, and more if required. The string-attaching device of my banjo receives knotted strings as well as looped strings, 25 either kind being attachable as readily and securely as the other, and as readily removable.

Another feature of my invention is a hinged cover which serves not only to cover 30 up the looped or knotted ends of the strings, but also serves as a means for placing pressure on the bridge of the instrument, whereby the bridge is held down firmly on the head.

35 A further feature of my new tailpiece consists in the provision of pins which are so arranged as to relieve the strain on the knotted ends of the strings.

The foregoing and other features and advantages of my invention will become apparent from a description of the accompanying drawings which illustrate a preferred embodiment of my invention.

In these drawings—

45 Figure 1 is a top plan view of the rear section of a banjo provided with my new tailpiece, the cover of the tailpiece being partly broken away to show certain parts beneath, this view illustrating how the 50 looped strings are attached to the tail-piece;

Fig. 2 is a section on line 2—2 of Fig. 1, looking in the direction of the arrows;

55 Fig. 3 is a rear view of my new tailpiece; and

Fig. 4 is a view similar to Fig. 1, with the

cover turned back, this view illustrating how knotted strings are attached to the string-receiving device of the tailpiece.

To the rim 1 of a musical instrument like 60 the banjo, or of the banjo type, is secured the usual screw 2 which passes into the stick 3 of the instrument. The headed screw 2 carries a bolt 3 to which my new tailpiece is connected, as will presently be explained. 65

My new tailpiece comprises a base-plate which I have indicated as a whole by B. This base-plate, which is preferably made of metal, consists of a main section 4, a turned down section 5, and a rear extension 70 6. The main section 4 of the base-plate is adapted to lie over and close to the head 7 of the instrument, as shown in Fig. 2. The turned down section 5 is practically at right angles to the main section 4 and lies against 75 the hoop 8 of the instrument. The rear extension 6 is provided with an opening through which projects the headed end of the bolt 3. The tailpiece is, therefore, pivotally connected with the bolt 3. 80

The base-plate B is provided with a string-receiving member 9, which is rigidly secured in place by any suitable means, such as the rivets 10 or the like. By forming the string-receiving member 9 with a turned-down portion 11, which lies against the turned-down portion 5 of the base-plate B, the latter is strengthened or reinforced at the angle connecting the sections 4 and 5. The member 9 is at its front end provided with a 90 series of upturned lugs 12 adapted to receive the ends of the strings. The lugs 12 are slightly spaced from each other, as shown in Figs. 1 and 4. These spaces are narrower than the width of the knotted end 95 of the smallest string to be used on the instrument, so that the knotted end of the string may be placed in the required space and firmly held therein, as indicated in Fig. 4. Figs. 1 and 2 show how looped strings are 100 attached to the lugs 12. To prevent the accidental detachment of the looped and knotted strings, the lugs 12 are hook-shaped, as best shown in Fig. 2.

It will be clear from the foregoing that my 105 new tailpiece receives looped strings and knotted strings equally well. In instruments of the banjo or mandolin type, or a combination of both, the wire strings are looped, as shown in Fig. 1, while the gut-strings and silk-strings are knotted, as indicated in Fig. 4. My new tailpiece may,

therefore, be used equally well on either type of instrument. Although I have shown in the drawings eight string-receiving lugs 12, having seven string-receiving spaces between them, the number of lugs may be less than eight or more than eight. My reason for showing eight lugs is, that at the present time I prefer a tailpiece with that number of lugs, so that the tailpiece may be used on instruments requiring four, five, six or eight strings.

The string-receiving lugs 12 are preferably formed on a separate member 9 which is rigidly secured to the base-plate B, but if desired, these lugs could be rigidly provided thereon in any other suitable manner. I prefer to use the angular piece 9 because, as above stated, it reinforces the tailpiece at the angle formed between the sections 4 and 5 of the base-plate.

In order to relieve or lessen the strain on the knotted ends of the strings held in the spaces between the lugs 12, I provide a plurality of pins 13, arranged approximately as in Figs. 1 and 4. It will be seen from these figures that the strings pass around the first row of pins and then are turned laterally to engage the second row of pins, so that the strain on the knotted ends is greatly relieved. When I say that the strings are turned laterally in passing from the first to the second row of pins, and from there to the bridge, I mean that they pass at an angle to the longitudinal axis of the instrument. This axis may be considered to be represented by the section line 2—2 of Fig. 1, or by the central string α in Fig. 4. There is no pin in engagement with the central string in Fig. 4, because that is a heavy string and does not require an interposed pin to lessen the strain on its knotted end. In the case of the looped wire strings, owing to their inherent strength, the strain-relieving pins 13 are not really essential, that is why in Fig. 1 some of the strings are not shown as passed around the pins 13.

The tailpiece is provided with a cover indicated as a whole by C. This cover is pivotally connected to the base-plate B in any suitable manner. The section 4 of the base-plate B is provided with upturned side flanges 14, on which rests the cover C when closed. As best shown in Fig. 2, the side flanges 14 follow the configuration of the cover, so that they form in effect the sides of a flat box. In Fig. 2, the forward end of the flange 14 is indicated at 14'. The cover C is provided with a pair of downturned ears 15. The flanges 14 are at their rear ends provided with a pair of openings in alignment with the openings in the ears or lugs 15, and through these aligned openings passes the pivot rod 16. I provide adjustable means for locking the cover in place. In the broad aspect of my invention, this adjustable

cover-locking means may assume various forms. In the drawings I have shown, for the sake of illustration, a locking means consisting of a clamp 17 provided at its ends with upturned extensions 18, adapted to overlie the sides of the cover, as clearly shown in Fig. 1. The clamp 17 is slidably mounted on the base-plate B by any suitable means, such as the headed guide pin 19 secured to the clamp and passing through the slot 20 of the base-plate. The cover C is provided at its sides with a pair of notches 21, as shown in Figs. 1 and 4. When the clamp 17 is moved from the position shown in Fig. 1 to the position shown in Fig. 4—70 that is to say, from the front end of the slot 20 to the rear end—the upturned ends 18 of the clamp 17 come into alignment with the notches 21 of the cover, so that the latter is free to be turned back on the hinge 16, as 75 shown in Fig. 4.

Other cover-securing means may be provided—such as a threaded bolt which would pass through the cover plate into a screw-threaded opening in the base-plate B, and which could be adjusted in the opening or removed altogether. However, I prefer to use a device like the clamp 17 which is mounted on the base-plate and cannot be removed therefrom, so that there is no 95 danger of losing it.

The cover C is not only used for covering up the knotted and looped ends of the strings attached to the tailpiece, but also serves as a means for placing the strings 100 under pressure near the bridge of the instrument, whereby the bridge is firmly pressed down on the head. For this purpose, the cover C extends forwardly to within a short distance of the bridge 22 105 of the instrument. Preferably, the forward end of the cover is slightly rounded or turned up, as indicated at 23.

The adjustability of the clamp 17 serves not only to release the cover, but also to 110 adjust the position of the string-engaging end 23 of the cover. If the clamp 17 is shifted toward the right (as viewed in Figs. 1 and 2), the forward end 23 of the cover will be slightly elevated under the 115 tension of the strings. The cover C is preferably made of a suitable material, such as sheet metal, which will yield at the free end of the cover under sufficient pressure. As a matter of fact, the entire tailpiece rises 120 slightly from the rear portion toward the front portion when in actual use. I have not attempted to indicate this exact position in Fig. 2, where the base-plate B is shown approximately parallel with the 125 head 7.

In order that the tailpiece may be adjusted and held in true central position, I provide adjusting means, such as the screws 24, 130 which pass through the double thickness of

the turned-down sections 11 and 5 of the member 9 and base-plate B, and which bear against the hoop 8 of the instrument. By means of these two screws, the tailpiece may 5 be so adjusted about the pivot screw 3, that it will be in true central position to insure the proper spacing of the strings on the finger-board.

It will be clear from the foregoing that I 10 have provided a tailpiece of simple construction, which is equally well adapted to receive looped strings and knotted strings, and which is capable of being used on banjos of a varying number of strings. In my 15 new tailpiece, the strings are quickly attached and quickly removed. The cover-plate C hides the mess of knotted or looped strings and prevents the sharp ends of wire strings from tearing the clothes of the 20 player. The cover C may be made of ornamental metal, so as to make the entire tailpiece not only a mere mechanical device for attaching strings, but serve as an ornament as well.

25 Although I have shown in the drawings a specific form of tailpiece, I would have it understood that I do not intend to be limited to the details herein set forth, as obviously it is possible to make changes and 30 modifications without departing from the invention as defined in the appended claims.

Having thus described my invention, what I claim as new and desire to secure 35 by Letters Patent of the United States, is:

1. A banjo, or the like, provided with a tailpiece comprising a base-plate secured to the rim of the instrument and extending over the head toward the bridge, a plurality 40 of slightly spaced lugs projecting upwardly from said base-plate and constructed to receive the looped ends of wire strings, the spaces between the lugs being of less width than the knotted end of a gut-string or silk- 45 string, and a plurality of fixed pins extending upwardly from said base-plate and arranged in two rows in such a way that the strings pass at an angle to the longitudinal axis of the instrument from the first row of 50 pins to the second row of pins and from there over the bridge, whereby said pins serve to relieve the strain on the ends of the strings.

2. A banjo, or the like, provided with a 55 tailpiece comprising a base-plate secured to the rim of the banjo and extending over the head toward the bridge, a member secured to said base-plate, a series of eight lugs projecting upwardly from said member and 60 slightly spaced from each other, the ends of the strings being attached to said slightly spaced lugs, the spaces between said lugs being of less width than the knotted end of a banjo string, and two rows of four pins 65 each extending upwardly from said base-

plate between said lugs and the bridge of the instrument, said two rows of pins being so arranged that the strings pass around said pins at an angle to the longitudinal axis of the instrument in passing from the 70 lugs to the bridge, whereby said pins serve to relieve the strain on the ends of the strings.

3. A banjo, or the like, provided with a tailpiece comprising a base-plate secured to 75 the rim of the banjo and extending over the head toward the bridge, means on said base-plate for attaching the ends of the strings, a cover movably connected with said base-plate and extending over the same toward 80 the bridge to within a short distance thereof, the forward end of said cover bearing down on the strings and exerting pressure thereon as they pass from under the cover over the bridge, and means for holding said cover in 85 closed position, said means being adjustable to release said cover.

4. A banjo, or the like, provided with a tailpiece comprising a base-plate secured to the rim of the banjo and extending over the 90 head toward the bridge, means on said base-plate for attaching the ends of the strings, a cover movably mounted on said base-plate and extending over the same toward the 95 bridge to within a short distance thereof, the forward end of said cover bearing down on the strings and exerting pressure thereon as they pass from under the cover over the bridge, and a clamping device on said base-plate to hold said cover in closed position, 100 said device being readily adjusted to release said cover.

5. A banjo, or the like, provided with a tailpiece comprising a base-plate secured to the rim of the banjo and extending over the 105 head toward the bridge of the instrument, means on said base-plate for attaching the ends of the strings, a cover hinged to the rear of said base-plate and extending forwardly over the same toward the bridge, the 110 forward end of said cover bearing down on the strings and exerting pressure thereon as they pass from under the cover over the bridge, and means for holding said cover in closed position, said means being adjustable 115 to release the cover and allow it to be thrown back on its hinge, the position of said adjustable cover-holding means also varying the pressure of the forward end of said cover on the strings.

6. A banjo, or the like, provided with a tailpiece comprising a base-plate secured to the rim of the banjo and extending over the head toward the bridge, means on said base-plate for attaching the ends of the strings, 125 and a cover adjustably mounted on said base-plate to cover the ends of the strings and to engage the strings at points on a line near the bridge to hold them close to the head.

7. A banjo, or the like, provided with 130

tailpiece comprising a base-plate secured to the rim of the banjo and extending over the head toward the bridge, a plurality of slightly spaced lugs projecting upwardly from said base-plate to which lugs the ends of the strings are attached, the spaces between the lugs being of less width than the knotted end of a banjo string, a plurality of fixed pins extending upwardly from said base-plate and so arranged that the strings pass from said lugs to said pins and from there to the bridge at an angle to the longitudinal axis of the instrument, whereby said pins serve to relieve the strain on the ends of the strings, a cover hinged at its rear end to said base-plate and extending over said lugs and pins, and adjustable means for holding said cover in place.

8. As a new article of manufacture, a

tailpiece for banjos, or the like, comprising a base-plate having a main section adapted to extend closely over the head of the instrument when the tailpiece is secured in position, said base-plate also having a short section approximately at right angles to the main section and adapted to be connected with the usual bolt or screw on the rim of the instrument, lugs carried by the main section of said base-plate for receiving and holding the ends of strings, a cover adjustably mounted on and extending over the main section of said base-plate, and means mounted on said base-plate for holding said cover in closed position, said means being adjustable to release the cover.

In witness whereof, I hereunto subscribe my name this 5th day of January, 1918.

ALBERT D. GROVER.
